UNITED STATES PATENT OFFICE.

JOHN ROBERT MCFARLIN, OF PHILADELPHIA, PENNSYLVANIA, ASSIGNEE TO ELECTRIC SERVICE SUPPLIES COMPANY, OF PHILADELPHIA, PENNSYLVANIA, A CORPORATION OF PENNSYLVANIA.

MULTIGAP LIGHTNING ARRESTER.

Application filed January 11, 1922. Serial No. 528,491.

My invention relates to lightning arresters of the so called multi-gap type and my primary object is to provide improved means of high efficiency, as well as simple, convenient and durable construction, for protecting electrical apparatus from lightning and other high voltage disturbances, by discharging such disturbances to ground and effectively preventing a following flow of dynamic or line current from continuing through the arrester to ground.

Desiderata attained by my invention are high efficiency in protecting electrical apparatus from various classes of lightning or high voltage disturbances; the capacity for successfully discharging charges of light or heavy volume, relatively low or high voltage and low or high frequency, and flexibility in the assembly and adjustment of its constituent parts with adaptability to efficient operation under varying conditions encountered in service.

My invention, in its preferred form, comprises an insulating housing having a sealed top containing a plate electrode provided with a lug, into which top the lead from the line wire passes to a connection with the lug, and a bottom provided with an opening through which the lead from the ground wire enters to a connection with a plate electrode on said bottom, in combination with a series of dished conducting discs, a series of insulating and non-inductive resistance spools disposed between discs spaced thereby to form spark gaps, the resistance spools varying in size and resistivity, and an insulating bolt passing through said plate electrodes, conducting discs and resistance spools to clamp them together.

The characteristic features of my invention are fully set forth in the following description and the accompanying drawings in illustration thereof.

In the drawings, Fig. 1 is an elevation of a lightning arrester embodying my improvements; Fig. 2 is a central longitudinal sectional view of same, and Fig. 3 is a broken section mainly on the line 3-3 of Fig. 2.

In the form of my improvements illustrated in the drawings, an insulating housing 1, adapted to be supported as on a pole, has a cap 2 cemented on its top. A plate electrode 3, containing a central opening 4, is fixed by the cap 2 on the body 1 and has

a part 5 projecting beyond the body into the recess 6 of the cap for connection through the recess with the lead 7 to the line wire.

A dished metal disc or ring 8, containing the central aperture 9 and having the flat peripheral ridge 10, has its plane central or body portion disposed in engagement with the lower surface of the plate 5, with the circular peripheral ridge extending downwardly. An insulating spool 11 is placed in engagement with the body portion of this disc, within its downwardly projecting ridge. A second similar metal disc 8 is placed in engagement with the insulating spool 11 in reverse relation to the first disc, with its circular ridge projecting upwardly, the circular ridges of the two discs being so disposed as to form terminals with an air gap 12 therebetween. Further similar discs 8 and spools 13 formed of conductive material having a relatively high ohmic resistance, as for example 100,000 ohms each, are arranged in columnar relation concentric with and similarly to the arrangement of the previously described discs 8 with the spool 11; the bodies of the discs between contiguous spools being in contact, their ridges projecting in opposite directions, and the air gaps 14 corresponding to the spools 13 being less than the gap 12, as here shown.

Metal discs 15 like the discs 8, but with deeper ridges, are separated by conducting spools 16 having a relatively low ohmic resistance as for example 50 ohms each, these discs and spools being arranged as previously described so that the plane surfaces of the discs between contiguous spools are in contact and the discs separated by the respective spools have their ridges disposed in opposite directions so as to provide air gaps 17 between them.

A plate electrode 18, supported within the bottom of the body 1, is engaged by the plane body portion of the lowermost disc 15, and the several discs and spools are clamped together by an insulating bolt 19 passing centrally therethrough, nuts or clamping members 20 and 21 on the ends of the bolt being disposed in recesses 22 and 23 of the top and bottom of the housing respectively. A lead 24 to the ground extends through an opening 25 in the bottom of the housing to a connection with the electrode 18.

This assembly secures accuracy of relationship between the parts as well as good electrical connections, while permitting ready assemblage in the desired relationship, ready adjustment of the relationship between the parts, and ready substitutions to vary the character of the resistance and the number or character of the air gaps, as may be desirable by reason of the service for which the mechanism is to be used.

In operation, when the line to which the arrester is connected is overcharged, the discharge to ground takes place through the arrester in a manner depending on the frequency of the discharge, its volume and other characteristics.

When a slight accumulation of static discharges to ground, it will take the path through the parts 7 and 3 to the disc 8 in contact with the latter, thence across the air gap 12, thence through the engaging discs between the contiguous spools 11 and 13, and thence through the spools 13 and 16 by way of the discs between them to the lowermost disc 15, the plate 18 and the lead 24 to ground. This discharge of static, in breaking down the air gap 12, ionizes the air between the corresponding discs 8 and thus permits a flow of dynamic or normal current to ground through the path taken by the static discharge. But this flow of dynamic current will be very small being limited by the combined resistance of all the spools in series, and will be interrupted by the action of the air gap 12 at the first half cycle of the generator wave, or where the flow reverses and passes through zero value.

A heavier charge of static or lightning, in discharging through the arrester to ground, takes the path through the electrically connected parts 7, 3 and 8 to and across the air gap 12 and then, depending on its volume, may follow the path across one or more of the air gaps 14, through the consecutive spool or spools 13 which may be in line therewith, thence through the spools 16 to the plate electrode 18 and thence by the lead 24 to ground. Whether any given discharge will take the path across an air gap 14 or through a spool 13 corresponding thereto will depend on the voltage built up across the ends of the spool, this voltage being expressed as the product of the ohmic resistance of the spool and the current in amperes flowing through the spool. When this voltage becomes high enough, it will break down the air gap and as a consequence a large part of the discharge will take the path of least resistance across the gap rather than through the spool. This discharge of static or lightning, in breaking down the air gap 12 and one or more of the air gaps 14, ionizes the air in the respective gaps and so permits a flow of dynamic or normal current from line to ground over the same path

taken by the static discharge. This flow of dynamic current will be limited by the combined resistance of all the spools 13 and 16 through which it flows and it will be extinguished by the actions of the air gaps in its path at the first half cycle of the generator wave, or where the flow reverses and passes through zero value.

A still heavier charge of static or lightning, discharging through the arrester to ground, will take the path across all air gaps 12 and 14 around the corresponding insulating spool 11 and high resistance spools 13, and thence, depending on its volume, may take the path across one or more of the air gaps 17, thence through the consecutive spool or spools 16, the plate 18 and the lead 24 to ground. Whether any discharge will take the path across an air gap corresponding to a spool 16, or through such spool, will depend on the voltage built up across the ends of the spool, this voltage when high enough breaking down the air gap and the discharge therefore largely taking the path of least resistance across the gap rather than through the spool itself. This discharge of static or lightning, in breaking down the air gaps across which it flows, ionizes the air in the respective gaps and so permits a flow of dynamic or normal current from line to ground over the same path taken by the static discharge. This flow of dynamic current will be limited by the combined resistance of all the low resistance spools through which it flows and will be extinguished by the actions of the air gaps in its path at the first half cycle of the generator wave, or where the flow reverses and passes through zero value.

It will be evident that a large part of an extremely heavy discharge may flow through the arrester over a direct air gap path, such path offering the greatest freedom of discharge and consequently affording the most efficient protection to electrical apparatus. In such case, the flow of dynamic or normal current following the discharge to ground will not be limited by any of the resistance spools within the arrester, but the functioning of the arrester is such that as the resistance spools are progressively eliminated from the discharge path, additional air gaps are automatically interposed in the path to extinguish the flow of current. The flow being assumed to be extremely large, all of the air gaps act to extinguish the current at the first half cycle of the generator wave, or where the flow reverses and passes through zero value.

The flattened ridges or terminals of the metal discs provide a substantial area from which discharges may occur, avoiding the burning and pitting that takes place in angular and rounded terminals and thus prolonging the lives of such discs.

The faces of the conducting spools 13 and 16 are covered with a coating material such as copper to afford good electrical contact between such spools and the metal discs or 5 spark gap electrodes engaged thereby.

In these spark gap elements, the construction is such that the spark takes place between quite exposed surfaces as distinguished from constructions in which the electrodes 10 are held in concavities of spacing blocks and the spark taking place in a small enclosed space.

This invention, it will be seen, provides means whereby the character of the discharge 15 determines the proper discharge path automatically, to afford the utmost freedom in discharging static or lightning charges from line to ground and the maximum protection to apparatus from charges of widely varying 20 character.

The mechanism shown and described, by way of exemplifying an embodiment of my

invention, may be variously modified, as by increasing or diminishing the number and spaces of the air or spark gaps; the number, resistivity and arrangement of the spools and otherwise within the scope of the claim. 25

Having described my invention, I claim:

A lightning arrester comprising a plurality of pairs of contacting gap electrodes having oppositely projecting peripheral ridges, hollow spools within said ridges and each 30 spacing an electrode of one pair from an electrode of an adjacent pair, said spools being of different resistivities, and an insulating rod passing through said spools and spaced from the inner surfaces thereof, said 35 rod having thereon means for clamping said spools and electrodes together. 40

In testimony whereof I have hereunto set my hand, this 9th day of January, 1922.

JOHN ROBERT McFARLIN.
